UNITED STATES PATENT OFFICE.

WILLIAM KUNDEL, OF HOBOKEN, NEW JERSEY.

WASHING BRUSH.

Application filed September 20, 1924. Serial No. 738,850.

To all whom it may concern:

Be it known that I, WILLIAM KUNDEL, a citizen of Germany, having taken out first United States citizenship papers, and a resident of Hoboken, in the county of Hudson and State of New Jersey, have invented a new and Improved Washing Brush, of which the following is a full, clear, and exact description.

10 This invention relates to brushes and particularly to an improved washing brush especially adapted for washing automobiles wherein the washing liquid is applied simultaneously with the application of the bristles 15 to the surface to be washed.

Another object of the invention is to provide a washing brush of the fountain type wherein the entire liquid distributing structure may be utilized or only part thereof.

20 A still further object, more specifically, is to provide a washing brush of the fountain type wherein a controlling valve and operating handle are arranged at a convenient point, the valve being so formed as to be 25 readily adjusted to cause the liquid to pass out the end of the brush or either side or both places simultaneously.

In the accompanying drawing—

Figure 1 is a longitudinal vertical sectional view through a brush, disclosing an embodiment of the invention.

Figure 2 is a transverse sectional view through Figure 1, approximately on line 2—2.

35 Figure 3 is a side view of the handle and valve shown in Figure 1.

Figure 4 is an enlarged sectional view through Figure 3, approximately on line 4—4.

40 Figure 5 is a view similar to Figure 4 but showing the parts shifted to a different position.

Referring to the accompanying drawing by numerals, 1 indicates a tubular member 45 acting as a handle, said handle being provided with a covering member 2 of rubber or other desired material and a washer 3 acting as a guard. Connected in any suitable manner with the tubular member or handle 1 is a valve 4 formed with a ringed extension 5 adapted to receive the end of a hose, as for instance, an ordinary garden hose whereby water may be applied to the brush to act as washing liquid. The handle 50 55 1 is hollow as shown in Figure 1 and has fitted therein an extension 6 from the brush

body 7, which brush body is provided with suitable bristles 8, said bristles being of any desired or usual construction. Preferably the body 7 is made into two parts, namely, 60 parts 7' and 7" as illustrated more particularly in Figure 2. Each of these parts is rounded at the edges so as to present a substantially annular groove when the parts are together, said groove accommodating 65 the pipes 9 and 10, which pipes merge together at the forward end of the brush and at the opposite end one pipe extends a short distance into the handle 1 where it is supplied with a plug 11 and the other end extends through the valve 4 to which it is secured. A central pipe 12 is carried by the body 7 and is secured at one end to the valve 4 in any desired manner and at the opposite end is preferably flattened 70 for a short distance at 13, said flattened end being open whereby water may be discharged longitudinally from the brush. A pair of metallic plates 14 is secured to the respective body sections 7' and 7" by screws or other means, said sections extending into the handle 1 where they are locked in place and to the handle by a rivet or pin 15, which rivet extends through the tube or pipe 12 whereby all the 75 parts are locked together at this point. The valve 4 is provided with a casing 16 having a longitudinal bore 17 extending entirely therethrough, said bore at one end extending through the extension 5 and at the other 80 registering with the pipe 12. An auxiliary passage-way 18 is provided in the casing 16 which enters the key bore 19 at right angles to the passage-way 18 so that at a given time it may register with the opening 20 in 85 the key 21. This key may be held in place in any desired manner and is provided with a handle 22 whereby it may be readily turned. The key 21 is also provided with a main bore or passage-way 23 which is shown 90 in Figure 5 as registering with the passage-way 18.

When the parts are in the position shown in Figure 1, water is supplied to the pipe or tube 12 only and is discharged longitudinally from the brush. When the key 21 is moved to a position diametrically opposite to that shown in Figure 4, water is supplied to the pipes 9 and 10 only so that a spray from the end and both sides of the 95 brush will be provided, said spray being caused by water passing through the vari- 100 105 110

ous apertures 24 in these pipes, said apertures being spaced any desired distance apart and preferably arranged on opposite sides of the device. When the key 21 is turned to the position shown in Figure 3, water is supplied to both of the passageways 17 and 18 so that all of the pipes are supplied with water simultaneously. When it is desired to shut off the entire supply of water, the key 21 is moved to the position shown in Figure 4.

When operating the brush, the bristles 8 may be used without the use of any water or other washing liquid, the water or other washing liquid may be used without using the bristles or they may be used simultaneously so that there will be the washing action of the liquid and the friction of the bristles for cleaning purposes.

20 What I claim is:—

1. A washing brush, comprising a brush body provided with bristles and a handle extending from the end of the brush body longitudinally thereof, said handle being 25 hollow, a centrally positioned pipe extending through said handle and entirely through the brush body but not through the bristles, a second pipe extending around the brush body near the base of the bristles and 30 substantially through said handle, said first mentioned pipe being open at the end opposite the handle and the second mentioned

pipe being provided with perforations at the part surrounding the brush body, and a single valve for controlling the flow of 35 washing liquid to said pipes, said valve being connected with the end of said handle opposite that connected with said brush body.

2. A washing brush, comprising a body 40 supplied with bristles, a pipe extending longitudinally through the body of the brush and open at one end, a second pipe extending around the outer surface of said body along opposite sides and across one 45 end, means for connecting both of said pipes to a source of water supply, and manually actuated means for causing water to flow through either of said pipes or both pipes simultaneously. 50

3. A washing brush, comprising a brush body provided with a handle and with bristles, a pipe extending through said handle and through said brush body and a second pipe extending from one end of said body along one side of the body, across the end of the body and back to the first mentioned end along the opposite side of the body, said second pipe being perforated at the part in contact with the brush body, and 55 a valve carried by one end of said handle and operatively connected with both of said pipes for turning on and off water thereto. 60

WILLIAM KUNDEL.
